RADIAL FLOW TURBINE

Ragnar Olov Jacob Möller, Finspong, Sweden

Application December 10, 1943, Serial No. 513,744
In Sweden December 19, 1942

4 Claims. (Cl. 253—16.5)

1

Steam or gas turbines of the radial flow type are already known in which there are two or more axially spaced blade groups so arranged with relation to each other as to be passed by the driving fluid in succession. The object of this well-known construction is to reduce the radial length of the blading and improve the efficiency of the turbine at the same time.

The present invention has for its object to provide an elastic fluid turbine having two or more axially spaced blade groups which while preserving the advantages above referred to affords an improved driving fluid consumption and, in case of bleeding turbines, an improved turbine regulation too.

The invention is characterized, chiefly, by the fact that the axially spaced blade groups are separated from each other by a labyrinth packing or packings so as to represent two individual bladings each adapted to be operated by an individual one of two separately admitted, parallel streams of the elastic driving fluid.

Another feature of the invention involves that the division of the blade groups into two separate bladings by means of the labyrinth packing or packings has reference only to the high pressure section of the turbine, inasmuch as a single low pressure section common to all of the high pressure blade groups is provided, which receives the driving fluid as discharged from one or more such groups.

In the accompanying drawing three embodiments of the invention are illustrated.

Fig. 1 is an axial section of part of a turbine according to the first embodiment.

Fig. 2 is an axial section of a corresponding part of a turbine according to the second embodiment.

Figs. 3 and 4 show effect curves of the turbine shown in Fig. 1 and Fig. 2, respectively.

Fig. 5 is an axial section of part of a turbine according to the third embodiment.

With reference to Fig. 1, the reference numerals 1 and 2 designate the end portions or journals of the oppositely rotating turbine shafts. The journal 1 carries two turbine discs 3 and 4, the former being keyed to the conical end of the journal and the latter being secured to the journal by the engagement of its extended hub 5 in the boring of the hollow journal. The journal 2 likewise carries two turbine discs 6 and 7; in this case, however, the former only is directly attached to the journal, whereas the other disc is carried by the turbine disc 6 through the intermedium of a drum-like or cylindrical wall 55 of the labyrinth discs 12, 13 situated radially

2

8 formed integrally with the periphery of the turbine disc 6 and bolted at its opposite end to the turbine disc 7.

The radially extending passage formed by the space between the turbine discs 3 and 7 contains a blade group 9 and the radial passage between the turbine discs 4 and 6 contains a blade group 10. Provided in the radial passage between the turbine discs 7 and 4 which normally represents a connection between the blade groups 9 and 10, and may sometimes contain a blade group, is a labyrinth packing 11 the supporting discs 12, 13 of which are fastened to the turbine discs 7 and 4, respectively. By this means the two blade groups 9 and 10 are separated from each other, so that they are not contained in a continuous tortuous passage in which they are passed by the driving fluid in succession. Instead thereof, each blade group has its individual inlet and its individual outlet. Leading to the blade group 9 from an annular passage 15 formed in the turbine casing is a set of inlet ports 14 extending through the turbine disc 3. To said annular passage the driving fluid, which may be termed "steam" hereinafter, is admitted through the pipe 16. The blade group 9 communicates at its outer periphery with an exhaust chamber 17. Leading to the inner periphery of blade group 10 from an annular passage 19 formed in the turbine disc 6 is a set of inlet ports 18. The passage 19 receives steam through a pipe 20. A set of outlet ports 21 formed in the cylindrical wall 8 connect the outer periphery of blade group 10 with a separate exhaust chamber 22. Surrounding the annular passages 15 and 19 are overload or discharge chambers 23, 24.

The exhaust chambers 17 and 22 are separated from each other by means of labyrinth packings 25, 26, the axial thrusts of which balance each other substantially. In addition to the labyrinth packing 11 already referred to as situated between the two blade groups, a labyrinth packing 27 is inserted between the stationary turbine casing and the turbine disc 3, another labyrinth packing 28 being provided between the stationary turbine casing and the turbine disc 6. The labyrinth packing 11 acts not only to separate the blade groups 9 and 10 from each other but also to balance the axial thrusts as acting in both directions on the blade group 10. Leading through the turbine disc 4 and the labyrinth disc 13 to inner points of the labyrinth packing 11 are equalization ports 29 in such a way that the outer and inner diameters of the portions 50 of the labyrinth discs 12, 13 situated radially

outside said ports are substantially equal to those of the blade group 10, the axial thrusts of which will thus be balanced substantially. An equalization passage, indicated by the dotted line 30 in the drawing, forms a communication between the chambers 23 and 24 so that nearly the same pressure will exist on both sides with the exception of the inner portions of the labyrinth discs. Inevitable variations of the axial thrust may be compensated by thrust bearings.

In operation, a flow of steam is admitted through pipe 16 to the annular passage 15 and thence through the ports 14 to the centre of the blade group 9 to which the steam imparts its energy while passing outwardly therethrough and from which the steam is discharged into the exhaust chamber 17. Another flow of steam is admitted through pipe 20 to the annular passage 19 and thence through the ports 18 to the centre of the blade group 10. After imparting its energy to the blade group, this steam is discharged to the separate exhaust chamber 22. The two flows of steam which may be of the same initial pressure or of different initial pressures are controlled independently. Preferably, the steam pressures are chosen with a view to producing a lower back pressure in the outlet 17 than in the outlet 22. Through pipes 31 steam that has passed through the labyrinth packings 26 and 28 is allowed to escape to the outlet having the lowest back pressure.

The turbine above described presents better regulating conditions than the hitherto known turbines having two back pressures, that is to say, turbines of the bleeding type.

In hitherto known turbines of this type governed by throttling, the flow of steam has undergone a throttling operation two times, firstly, at its entrance into the high pressure section of the turbine and, secondly, at its entrance into the low pressure section thereof, after part of the steam has been discharged. This operation has caused losses, in part due to the throttlings themselves, since owing to the governing speed the throttlings cannot be made arbitrarily small, and in part, and above all, at partial loads, as the subdivision of the expansion into two stages impairs the efficiency of the partial loads.

The improvement resulting from the invention is diagrammatically illustrated in Fig. 3, which shows a curve representing the steam consumption at throttling. In turbines having blade groups coupled in series with respect to the flow of the driving fluid the whole turbine output follows curve a. In a turbine according to the invention, only the smaller blading 10 operating at the higher pressure follows curve a. The larger blading 9, on the contrary, which yields the main part of the output, follows the more favourable curve b.

In Fig. 2 the invention is shown as applied to a back pressure turbine proper. In this case the two blade groups are provided with a common exhaust chamber 17. By the removal of the separate exhaust chamber 22 of the blade group 10 also the labyrinth packings 25 and 26 may be dispensed with. The remaining elements are designated by the same reference numeral as the corresponding elements of Fig. 1.

Also in this case the admission pressures of the steam may be different, so that the turbine becomes a two-pressure turbine. In case of a mere back pressure turbine the two pressures, however, should be equal at full load. In such case the length of the blades should be so proportional

that the small blading 10 may yield up to 50% of the total output and the blading 9 the remainder.

The steam consumption of this turbine is diagrammatically indicated in Fig. 4. The curve d has reference to the blading 9 after deducting the losses appearing in blading 10, the curve e has reference to the blading 10 after deducting the losses appearing in blading 9, and the curve c has reference to an undivided turbine governed by usual throttling. By means of a suitable division of the steam between the two blade systems 9 and 10 it is possible to obtain a steam consumption corresponding to the dotted line (which in part coincides with d and e) when the two blade systems are arranged in parallel according to the invention.

In the embodiment shown in Fig. 5 the division of the blades so as to represent two or more axially spaced bladings adapted to be passed by two or more separate flows of driving fluid has reference only to the high pressure part of the turbine. In the low pressure part, on the contrary, there is but a single blade group that is common to all blade groups of the high pressure part and receives driving fluid as exhausted from one or more of these high pressure groups.

The shafts and the turbine discs are similar to those of the embodiments already described and designated by like reference numerals.

The blade group provided between the turbine discs 3 and 7 is subdivided in two sections, namely an inner or high pressure section 9¹ and an outer or low pressure section 9². The high pressure section 9¹ is substantially of the same radial extension as the blade group 10. The section 9¹ and the blade group 10 are each provided with an individual set of inlet ports 14 and 18, respectively. The blade group 10, however, has no separate outlet nor any exhaust chamber, in as much as the cylindrical connecting wall 8 between the turbine discs 6 and 7 has no outlet ports (as 21). Instead thereof the turbine disc 7 is formed with a set of ports 32 forming a communication between the axially extending angular passage 33 inside the cylindrical wall 8 and the space 34 between the blade group sections 9¹ and 9².

The exhaust steam from the blading 10 will thus mix in space 34 with the steam exhausted from the inner blade group section 9¹ and then flow together with the same through the common low pressure blades 9², the arrangement being such as to allow the discharge of steam from space 34 for consumption purposes or the admission of overload steam to the said space.

Due to the fact that the high pressure part of the turbine comprises parallel bladings, the turbine resulting will permit partial governing of the high pressure part which in case of partial loads means an improvement of the efficiency.

In case of small loads steam is admitted through the ports 18, while at the same time the admission of steam through the ports 14 is interrupted. The steam flow as supplied through ports 18 passes through the blade groups 10 and 9² in succession while imparting its energy to the blades of these groups. In case of larger loads steam may be admitted through ports 14, the admission of steam through ports 18 being interrupted. In this case the steam expands in the blade group sections 9¹ and 9². In case of still larger loads steam may be admitted from both sides, that is to say both through ports 14 and through ports 18 so that parallel flows of steam are supplied to the two high pressure bladings 9¹ and 10, while the flows discharged from said bladings will com-

bine before entering the common low pressure blading ⁹².

It is to be noted that the number of blade groups and the distribution thereof to separate bladings may be varied arbitrarily without departing from the principle of the invention.

What I claim is:

1. In a turbine of the class described, the combination of a stationary casing having two separate inlets for the driving fluid and at least one outlet for exhaust fluid, two oppositely rotatable shafts centrally mounted in said casing so as to extend in axial alinement with each other, at least four axially spaced turbine discs, two alternate ones of said discs being carried by one of said shafts, one of said other discs being carried on the other shaft, a wall secured on said one other disc and extending axially outwardly of one of the first two discs, the fourth disc being secured to the said wall and being located between the first two discs, a labyrinth packing provided between the inner two discs and serving with said discs and said wall as a partition to divide off in the casing two spaces, turbine blades carried by the respective turbine discs in said spaces, passage means to allow separate admittance of driving fluid to each space from a corresponding one of said inlets, the fluid from one of said spaces exhausting directly to a casing outlet, an opening in said partition for exhaust of fluid from the other space to a casing outlet, so located that the exhausting fluid does not pass through the packing, and labyrinth packings provided between the extreme turbine discs of both spaces and the respective inlets and outlet of the casing.

2. In a turbine of the class described, the combination of a stationary casing having two separate inlets and two separate outlets for the driving fluid and the exhaust fluid, respectively, two oppositely rotatable shafts centrally mounted in said casing so as to extend in axial alinement of each other, at least four axially spaced turbine discs, two alternate ones of said discs being carried by one of said shafts, the outer one of the other two discs being carried by the other shaft, a support extending axially from said outer disc and passing the inner disc of said one shaft radially outwardly thereof, and supporting the fourth disc between the first two discs, a labyrinth packing provided between the inner discs for dividing the space in which the discs are located into two parts, turbine blades located in said parts of the space and carried by the respective turbine discs, passage means being provided to allow separate admittance of driving fluid to each part of the space from a corresponding one of said inlets and separate discharge of exhaust fluid from each part to a corresponding one of said outlets, and labyrinth packings provided between the extreme turbine discs of both parts and the respective inlets and outlets of the casing, a communication being provided for passing balancing fluid to an inner point of said first-mentioned labyrinth packing from the inner end of the adjacent blade containing space part, the outer end of which communicates with the outer end of said packing, said communication comprising passages extending through the respective turbine disc.

3. In a turbine of the class described, the rotary system of which includes two oppositely rotatable shafts extending in alinement of each other, at least four axially spaced turbine discs, two alter-

nate ones of said discs including an inner disc being carried by one of said shafts, the end one of the other discs being carried by the other shaft, a supporting wall extending from said end disc axially to the other inner disc, a labyrinth packing provided in the space between the two inner ones of said turbine discs for dividing the space in which the discs are located into two parts, high pressure blades provided in one of said parts, other high pressure blades provided in the inner portion of the other part, low pressure blades provided in said last-mentioned part outside the high pressure blades thereof, a stationary casing in which said shafts are centrally mounted and which encloses the rotary elements of the turbine, said casing having a separate driving fluid inlet for each group of high pressure blades and a common outlet for exhaust fluid from all blade groups of the turbine, and said supporting wall being located at a greater diameter than the periphery of the adjacent inner disc, an opening through said other inner disc within said wall, said wall and opening constituting fluid conduction means between the inner end of the low pressure blade system and the outer end of the high pressure blade system of said first-mentioned group so that said low pressure system is fed with fluid discharged from the high pressure blades of both parts.

4. A turbine of the class described, the rotary system of which includes two shafts for opposite rotation, at least four discs, two alternate ones of said discs including an end disc and an inner disc being carried by one of said shafts, the other end disc being carried by the other shaft, an axially extending supporting wall extending from said other end disc radially outwardly of and axially beyond the adjacent inner disc, the other inner disc being carried by said wall, a labyrinth packing between the two inner ones of said oppositely rotatable turbine discs for dividing the rotary system of the turbine into two separate high pressure stages, blades for opposite rotation carried by said discs, a casing in which said shafts are mounted, said casing having a separate driving fluid inlet for each of said stages, an opening through said other inner disc at the outer end of one high pressure stage and within said wall providing a common high pressure exhaust fluid outlet, the rotary system of the turbine further including a single low pressure blading located between discs carrying one of the high pressure stages and at greater diameter than said high pressure bladings, said low pressure blading being in communication at its inner end with said common outlet adjacent said opening, said casing having a single outlet and said low pressure stage exhausting to said casing outlet.
